UNITED STATES PATENT OFFICE

115,901

DESIGN FOR A TIMEPIECE FACE

Stevan Banick, Astoria, Long Island, N. Y.

Application January 21, 1939, Serial No. 82,516

Term of patent 3½ years

To all whom it may concern:

Be it known that I, Stevan Banick, a subject of the King of Jugoslavia, but having taken out my first papers with the intention of becoming a citizen of the United States of America, residing at Astoria, L. I., in the county of Queens and State of New York, have invented a new, original, and ornamental Design for a Timepiece Face, of which the following is a specification, reference being had to the accompanying drawing, forming part thereof.

I claim:

The ornamental design for a timepiece face, as shown.

STEVAN BANICK.
